UNITED STATES PATENT OFFICE.

OLIVER S. JENNINGS, OF WILKINSBURG, PENNSYLVANIA, ASSIGNOR TO WESTINGHOUSE ELECTRIC & MANUFACTURING COMPANY, A CORPORATION OF PENNSYLVANIA.

SWITCH MECHANISM.

Application filed March 10, 1922. Serial No. 542,740.

To all whom it may concern:

Be it known that I, OLIVER S. JENNINGS, a citizen of the United States, and a resident of Wilkinsburg, in the county of Allegheny, and State of Pennsylvania, have invented a new and useful Improvement in Switch Mechanism, of which the following is a specification.

My invention relates to switch mechanism and particularly to safety enclosed switch mechanism of the double-throw type.

One object of my invention is to provide a switch mechanism of the enclosed double-throw type, wherein the switch is actuated to open or neutral position, or to either of its closed positions, with a snap action.

Another object of my invention is to provide a mechanism, having the above characteristics, wherein the actuating mechanism is mounted exteriorly of the housing and may be applied to standard double-throw switches having exteriorly extending operating shafts.

A further object of my invention is to provide a simple, inexpensive and effective mechanism for effecting operation of a double-throw switch with a snap action.

These and other objects, that will be made apparent throughout the further description of my invention, are attained by means of the switch mechanism hereinafter described, and illustrated in the accompanying drawings, wherein:

Figure 1 is a front view of a switch mechanism embodying features of my invention;

Fig. 2 is a longitudinal sectional view of the switch mechanism shown in Fig. 1, showing parts of the mechanism in side elevation;

Fig. 3 is a view, partially in section and partially in elevation, showing details of the switch-operating mechanism;

Fig. 4 is a longitudinal section through the switch-operating mechanism taken on the line IV—IV of Fig. 3, showing parts of the switch mechanism in elevation, and

Fig. 5 is an elevational view of the operating spring, showing its relation to parts of the mechanism.

Referring to the drawings, the apparatus includes a metal housing 6 in which is mounted an insulating panel 7. Upon opposite ends of the panel, two sets of switch

jaw members 8 and 9 are mounted that are adapted to be engaged by double-throw 55 switch-blade members 11 that are pivoted to centrally disposed pivot-jaw members 12.

The switch-jaw members 8 and 9 are provided with terminals 13 and 14 to which load conductors of an electrical circuit are 60 connected. The switch member 11 comprises two sets of blade members 15 and 16 that are adapted to alternately connect the terminals 17, connected to the pivot-jaw members 12, to the switch-jaw members 8 65 and 9.

Insulating plates 18 connect the blade members 16 and 15, and a rod 19, extending through the plates, serves to so connect the switch members 11 that they are actuated 70 simultaneously to open or neutral position or to either closed position. The plates 18 are provided with slots 21 through which a transversely extending operating bar 22 extends.

The ends of the operating bar are pivoted in the side walls 23 and 24 of the housing. The end 25 of the operating rod 22 is provided with a square portion 26 for the purpose of receiving a ratchet plate 27 that constitutes a part of the switch-actuating mechanism and which is located exteriorly of the housing.

It is an object of my invention to provide simple and inexpensive means for moving 85 the switch member to open or neutral position and to either closed position with a snap action. This object is accomplished by means of the following actuating mechanism, which includes an operating handle 28 90 that is preferably made of cast metal and provided with a housing 29 which surrounds an enclosed operating mechanism.

The ratchet plate 27 is mounted upon the square end of the operating rod 22 and is 95 provided with teeth or stop seats 31 and 32 that are disposed upon one side of the axis of the ratchet plate, and 33 and 34 that are disposed on the opposite side thereof and which face in opposite directions. The 100 ratchet is also provided with an extension 35 that is adapted to engage stop seats 36 and 37 that are mounted interiorly of the housing 29 for limiting the relative movement of the housing or operating handle with respect 105 to the ratchet member or the switch member.

The operating handle and the switch member are yieldingly connected by means of a helical driving spring 38 that is mounted interiorly of the housing and which terminates in inwardly projecting terminal portions 39 and 40 that are disposed on opposite sides of two overlapping pins 41 and 42. The pin 41 is riveted to the housing 29, and the pin 42 is secured to the ratchet member 27 at a point intermediate the two sets of stop seats or teeth.

The housing 29 is pivoted, for rotary movement, upon a shaft 43 that is secured to a bracket 44 which is attached to the side 23 of the housing by means of screws 45.

A plate 46 is mounted upon the side wall 23 and carries two projecting pins 47 and 48, upon which latch pawls 49 and 51 are pivoted, respectively, the ratchet-engaging ends of the pawl members are biased towards the ratchet plate by means of a leaf spring 52 that is disposed between the free ends of the latch pawls in notches 53 provided for retaining the spring 52 in assembled relation of the latch pawls.

Cam members 54 and 55 are cast integral with the housing, the former having two prominent cam portions 56 and 57 that are adapted to successively engage the free end of the latch pawl 49 when the operating handle is moved in a counter-clockwise direction. The cam 55 is provided with two prominent cam portions 58 and 59 that are adapted to successively engage the free end of the latch pawl 51 when the operating handle is moved in a clockwise direction.

As indicated in Figs. 2 and 3, the switch member is in the closed position wherein the terminals 17 and 14 are connected. The latch pawl 49 is in engagement with the stop seat 32 of the ratchet 27. Counter-clockwise or opening movement of the switch is prevented by the latch pawl 49.

Movement of the operating handle 28 toward open or neutral position, which is midway between closed position, causes the pin 41, carried by the housing 29, to engage the spring terminal 39 and to bias the spring terminal 40 against the pin 42 that is carried by the ratchet member 27.

After the handle 28 is moved beyond a position midway between the closed positions, the cam 56 engages the free end of the pawl 49 and withdraws it from engagement with the stop 32. The spring 38, which, at this time, is under tension against the pin 42, causes the switch member 11 to be moved to open position with a snap action, this movement being arrested by the latch pawl 49 which engages the stop seat 31 of the ratchet member when the switch member has reached open position.

At this time, the nose of the latch pawl 51 is forced into engagement with the stop seat 33 of the ratchet member and prevents

clockwise movement of the switch member. It will be seen, therefore, that the switch is locked in neutral position by the latch pawls. When the hand of the operator is removed from the operating handle, it will return to the neutral position with respect to the operating member in response to the centering action of the spring 38.

In order to connect the terminals 17 with the terminal 13, the operating handle is further moved in a counter-clockwise direction and, after it has been moved a predetermined distance, the cam 57 engages the free end of the latch pawl 49 and releases it from engagement with the stop seat 31. The spring 38 is again biased by the relative movement of the operating handle with respect to the switch member and causes the blade member 16 to be moved to closed position with the contact jaw members 8 with a snap action. At this time, the nose of the latch pawl 51 moves into engagement with the stop seat 34 of the ratchet member 37 and retains the blades 16 in closed position.

To open the switch, the operating handle is turned in a clockwise direction until the cam 58 engages the free end of the latch pawl 51 and withdraws it from engagement with the stop seat 33. The nose of the latch pawl 51 will arrest the opening movement of the switch member by reason of its engagement with the stop seat 33. The latch pawl 49 will, at this time, fall into engagement with the stop seat 31 and cause the switch member to be locked in open position. Further clockwise movement of the operating handle 28 will cause the cam 59 to engage the latch pawl 51 and release it from engagement with the stop seat 33. The spring 38 will then cause the switch member to be moved to closed position with a snap action.

Should the switch-blade member adhere to the switch-jaw members so that the tension of the spring is insufficient to cause opening movement, the switch-blade members may be positively actuated to open position by the operating handle. In this event, the seats 37 or 36 positively engage the projection 35 on the ratchet member 27 and cause movement with the handle.

It will be seen that the device is relatively simple and contains relatively few parts, and may be applied to boxes of standard construction.

While I have described and illustrated but one embodiment of my invention, it will be apparent to those skilled in the art that various changes, modifications, substitutions, additions and omissions may be made therein without departing from the spirit and scope of my invention as set forth in the appended claims.

I claim as my invention:

1. Switch mechanism comprising a mov-

- able switch member, an operating handle therefor having a lost-motion connection thereto, a spring for connecting the operating handle to the switch mechanism and for moving the switch mechanism in response to movement of the handle, stop members on the switch member, a latch for successively engaging the stop members for retaining the switch member in predetermined positions and cam members on the handle for successively engaging the latch whereby the latch is successively released from the stop members by a progressive movement of the handle in one direction.
- 15 2. Switch mechanism comprising a double-throw switch member, an operating handle therefor having a lost-motion connection thereto, two pairs of stop members on the switch member, a latch for each pair for successively engaging the stop members for retaining the switch member in predetermined positions, and cam members on the handle for successively engaging one of the latches whereby the said latch is successively released from the stop members by a progressive movement of the handle in one direction.
3. Switch mechanism comprising a movable switch member, an operating member therefor having a lost-motion connection thereto, a spring for connecting the operating member to the switch member and for moving the switch member in response to movement of the operating member, stop members on one of the members, a latch having a stationary pivot for successively engaging the stop members for releasably retaining the switch member in predetermined positions, and cam members on the other of first said members for successively engaging the latch whereby the latch is successively released from the stop members by a progressive movement of the operating member.
- 45 4. Switch mechanism comprising a double-throw switch member, a ratchet member carried by the switch member having two sets of ratchet teeth facing in opposite directions, a latch pawl for each set of teeth for limiting movement of the switch members in either direction and at predetermined points, an operating member movable relatively to the switch member, a driving spring for yieldingly connecting the switch member to the operating member, and cam members actuated by the operating member for moving the latch pawls to releasing position.
- 50 5. Switch mechanism comprising a double-throw switch member, a ratchet member carried by the switch member having two sets of ratchet teeth facing in opposite directions, a latch pawl for each set of teeth for limiting movement of the switch members in either direction and at predetermined points, an operating member movable relatively to the switch member, a driving spring for yieldingly connecting the switch member to the operating member, and cam members actuated by the operating member for moving the latch pawls to releasing position.
- 55 6. Switch mechanism comprising a double-throw switch member, a ratchet member carried by the switch member having two sets of ratchet teeth facing in opposite directions, a latch pawl for each set of teeth for limiting movement of the switch members in either direction and at predetermined points, an operating member movable relatively to the switch member, a driving spring for yieldingly connecting the switch member to the operating member, and cam members actuated by the operating member for moving the latch pawls to releasing position.
- 60 7. Switch mechanism comprising a double-throw switch member, a ratchet plate carried thereby and having two sets of stop teeth facing in opposite directions, a latch pawl for each set of ratchet teeth for limiting movement of the switch member in either direction and at predetermined points, an operating member movable relatively to the switch member, a pin secured to and extending from the ratchet member, a pin secured to and extending from the operating member and overlapping the pin secured to the ratchet member, a spring for yieldingly connecting the said pins and for imparting movement to the switch members in response to movement of the operating member, and cam members carried by and movable with the operating member for tripping the latch pawls when the operating member is moved to predetermined positions.
- 65 8. Switch mechanism comprising a rotatable switch member, a rotatable operating handle therefor having a lost-motion yielding connection to the switch member, a toothed ratchet member secured to the switch member, a latch pawl for engaging the ratchet member and arresting movement thereof in successive predetermined positions and cam means for tripping the latch pawl for releasing the switch member in response to a predetermined progressive movement of the handle.
- 70 9. Switch mechanism comprising a rotatable switch member, a rotatable operating handle therefor constituting a casing and having a lost-motion yielding connection to the switch member, a toothed ratchet mechanism part of which is carried by the switch member for arresting movement thereof in successive predetermined positions and cam means carried within the casing for releas-

- ing the ratchet mechanism to permit movement of the switch in response to a predetermined progressive movement of the handle in either direction.
- 5 10. Switch mechanism comprising a rotatable switch member, a rotatable operating handle therefor constituting a casing and having a lost-motion yielding connection to the switch member, a toothed ratchet member secured to the switch member, a latch pawl for engaging the ratchet member and arresting movement thereof in successive predetermined positions and cam means carried by the casing and disposed interiorly thereof for tripping the latch pawl for releasing the switch member in response to a predetermined progressive movement of the handle in either direction.
- 10

In testimony whereof, I have hereunto subscribed my name this 25th day of February, 1922.

OLIVER S. JENNINGS.
